United States Patent Office

Des. 211,461
Patented June 18, 1968

211,461

SWIVEL CHAIR

Thomas G. Walkinshaw, Shawnee Mission, Kans., assignor to Cramer Industries, Inc., Kansas City, Kans., a corporation of Missouri

Filed Apr. 5, 1967, Ser. No. 6,541

Term of patent 14 years

(Cl. D15—1)

FIG. 1 is a perspective view taken generally from the front of a swivel chair embodying my design.

FIG. 2 is a perspective view taken generally from the side of the chair.

FIG. 3 is a perspective view taken generally from the rear of the chair.

The dominant features of my design reside in those portions shown in full lines on the drawing.

I claim:

The ornamental design for a swivel chair, as shown and described.
